COMBINATION CAP AND CLIP FOR PENS,
PENCILS OR SIMILAR ARTICLESJohn W. Gardner, Hermosa Beach, Riccardo A. Favilli, Redondo Beach, and Ray Wever, La Canada, Calif.,
assignors to Mattel, Inc., Hawthorne, Calif.

Filed Aug. 7, 1972, Ser. No. 278,688

Term of patent 14 years

Int. Cl. D19—06

U.S. Cl. D74—17 A

FIG. 1 is a front elevational view of the combination cap and clip for pens, pencils or similar articles showing our new design;

FIG. 2 is a rear elevational view thereof;

FIG. 3 is a left side elevational view thereof;

FIG. 4 is a right side elevational view thereof;

FIG. 5 is a top plan view thereof; and

FIG. 6 is a bottom plan view thereof.

We claim:

The ornamental design for a combination cap and clip for pens, pencils or similar articles, as shown.
